DISK CLUTCH

Filed Sept. 16, 1926

INVENTOR.
Otto W. Hahn

BY
Carlos P. Griffin
ATTORNEY.

UNITED STATES PATENT OFFICE.

OTTO W. HAHN, OF SAN FRANCISCO, CALIFORNIA.

DISK CLUTCH.

Application filed September 16, 1926. Serial No. 135,748.

This invention relates to improvements in disk clutches, an object of which is to provide means whereby the operation of the disks of the clutch may be extended over a greater distance than is the case with the ordinary disk clutch; the object being to give a softer action to prevent so called "grabbing" of the clutch.

This invention is intended to provide a spring means for engaging the disks of disk clutches which will cause the time engagement to be increased from first contact to ultimate-pressure contact, as well as to increase the distance through which the disks in contact will move from initial contact to final pressure contact and it is applicable to any present type of disk clutches. This construction will automatically cause the disks of the clutch to move through a greater distance than similar clutches not so equipped and will give a gradually increasing and gradually diminishing pressure on the disk faces when the clutch is engaged or disengaged.

Another object of the invention is to provide a substantially flat flexible disk or annulus which can be installed in any disk clutch without changing its construction, to improve the operation thereof, either one or two of these members being used in such clutches.

It will be understood by those skilled in the art that at the present time the use of corrugated plates in clutches is familiar, such plates for example as are seen in Patent 1,340,885 but the difficulty with such plates is that each corrugated plate rubs against an adjacent plate with the result that the spring effect of the corrugated plates is injured in a short time, and in any event such plates cannot be used where they bear upon other plates faced with asbestos wearing surfaces, for the reason that they tear out the asbestos.

An object, therefore, of the present invention is to provide a spring disk or annulus so located that it will have no relative movement with respect to the plate upon which it bears, its action being to increase the period of contact between the position of the first contact and the position of the final contact.

It will also be understood by those skilled in the art that with the ordinary dry plate clutch that the driving engagement of the driven disk, and driving disk is a matter of not more than a thirty-second of an inch

between initial contact and final position so that even though this distance is multiplied by the leverages used on any given foot pedal that this time or distance engagement cannot be lengthened, and as the clutch wears itself smooth it becomes extremely small. This causes the clutch to engage with great force in a very short period of time. In the present case the springs used give a distance of movement of the driven disk or annulus with respect to the driving disk or annulus longitudinally of the driving shaft of approximately a quarter of an inch. The precise distance of movement of the disks or rings is determined by the height of wave or bend of the material forming the spring. This distance or disk movement multiplied by the leverages of ordinary foot pedals gives a distance of several inches, and in that way makes the clutch action much smoother and softer for the car driver there being no tendency of the clutch to jerk the car when suddenly engaged.

In the present case two such springs have been shown but only one spring has been used and has been found to work satisfactorily.

It will also be apparent that while one character of spring has been shown in the present case that the same effect may be attained with other forms of springs acting upon the last disk of the series. Springs of this character will, of course, act with an increasing spring pressure from the time of the beginning of the contact of the plates with each other, and with an increasing pressure up to the time the full friction driving effect is applied to them by the pressure of the large compression spring. In this way the auxiliary springs act as an engaging force against the plates independently of the large spring, the large spring being held from complete engagement with the disk plates until finally released by the foot whereupon the lighter springs substantially pass out of action as far as the development of friction is concerned, but during the intermediate positions give the gradually increasing pressure of engagement upon the disks so highly desired to effect a smooth starting of the car.

Another object effected by the spring disks or annuli described herein is to provide the clutch with an automatic flexible contact between the driven and driving members which is capable of correcting defects of alignment

of said members and which is in operation throughout the engaging and disengaging periods of the clutch disks, as well as when the clutch is running under full load. The 5 result of this is that the driven clutch unit is flexibly connected to the driving clutch unit notwithstanding the fact that the pressures on the disks are heavy enough to effect the necessary driving force. A second result 10 of this application of the disks herein described is that during the period of engagement of the driving and driven disks that this spring disk or annulus will effect at all times an automatic equalization of pressures on 15 said disks.

Another result attained by this spring disk or annulus is that it will during the time of the engagement of the driving and driven disks of the clutch automatically change the 20 amount of slippage between said members and will always allow an amount of slip necessary for the smooth engagement of the clutch at any speed or load, and without allowing a continuous slippage to occur.

25 Other objects of the invention will be apparent as the description proceeds.

An embodiment of the invention is shown in the accompanying drawings in which the same reference numeral is applied to the 30 same portion throughout the several figures of the drawings and of which there may be modifications.

Figure 1 is a detailed view in vertical section of the clutch and driving member parallel to the driving shaft,

Figure 2 is a side elevation of one of the inner driving disks,

Figure 3 is a side elevation of one of the outer driving disks showing a break in one 40 of the asbestos rings used in connection therewith,

Figure 4 is a sectional view of the driving disk shown in Figure 3, on the dotted line 4-4 of Figure 3,

Figure 5 is a side elevation of one of the spring disks, and

Figure 6 is an edge view of one of the spring disks, said disks in actual practice being about $\frac{1}{16}$ th to $\frac{1}{4}$ of an inch from one 50 side to the other side across the corrugated portion, and being made of steel of approximately sixteen gauge sheet, although the exact thickness is immaterial to the present invention.

55 In the drawings the numeral 1 represents the fly wheel of an engine or other driving member, which fly wheel has the hub 2 secured to the driving shaft 3. The driven shaft is indicated at 4 and it has a shoulder at 5 to form an abutment for the spring washer 6.

The driving shaft 3 and the driven shaft 4 are held in alignment by means of a projection 7 on the driving shaft which extends 60 into a recess in the end of the driven shaft 4.

The fly wheel has a plurality of pins 8 extending therefrom, each of which is parallel to the shaft 4. Mounted on the end of the shaft 4 is a disk 9, which disk is provided with a series of pins 10 parallel to the pins 70 carried by the fly wheel. The pins 8 on the fly wheel are for the purpose of driving the disks 11, while the pins 10 are for the purpose of driving the inner disks 12. The outer disks have a plurality of ears 13 and 14 which engage the pins 8, while the inner disks have a plurality of ears 15 and 16 which engage the inner pins 10.

The outer rings have friction facing rings on each side thereof as indicated at 17 and 80 17', and while only five friction driving rings are illustrated in the present clutch, it is common to have a larger number, if desired.

Surrounding and slidable on the larger portion of the shaft 4 is a sleeve 19, said sleeve 85 being connected to a spring housing 20, which spring housing in turn has a ring 21 at its inner end screwed thereinto in substantially the same way as the sleeve 19 is secured to hold a heavy spiral spring 22 compressed when the 90 clutch is in use. Ordinarily some form of an anti-friction bearing 23 is used when it is desired to compress the spring 22 still more to release the clutch, any suitable means being used to connect said ball bearing to the foot 95 pedal.

It will be seen from an examination of Figure 1 that three of the rings 12 bear upon two of the friction material covered rings 11; the outer pair of rings 12 bear respectively upon one of the rings 25 against the disk 9, while the other one bears upon one of the rings 25 in engagement with the disk 26 carried by the housing 20. The rings 25 are made of tempered spring steel corrugated 105 radially to be about three-sixteenths to one quarter of an inch high when laid upon a flat surface, as indicated by the two dotted lines 27-28 on Figure 6, and the material is thin enough so that under a suitable pressure it 110 will flatten from one-eighth to three-sixteenths of an inch, dimensions being given merely to indicate the possible limits of action.

The operation of the clutch is as follows: 115 It will be seen that the outer rings 11 are engaged and driven by and rotated at all times with the pins 8, but they are longitudinally slidable with respect to said pins. Similarly the rings 12 are engaged with, and are 120 driven by, and rotate at all times with the pins 10, and with respect to which they are slidably longitudinally.

The rings 25 of which either one or two 125 may be used, do not have any driving ears or lugs, but simply ride loosely on the periphery of the pins 10, and they have no relative movement circumferentially with respect to the ring 12, but merely serve to increase the time and distance of engagement 130

of the driving and driven rings whereby the clutch is prevented from grabbing. It will thus be seen that both of the spring rings 25 shown in the present instance serve only 5 to move their adjacent rings 12 a short distance away from the two members 9 and 26 when the clutch is released. The clutch is released by pulling on the bearing 23 to the right, Figure 1, thereby still further 10 compressing the spring 22 and disengaging all of the disks of the clutch from each other.

When the clutch is to be engaged the pressure on the bearing 23 is released, the spring 22 is allowed to expand and it will to some 15 degree flatten the two springs 25 whereby sufficient friction is placed upon the driving and driven rings to start the car or other machinery to be driven, slow enough to prevent any breakage of the parts.

20 It will be further understood by those skilled in the art that while but one form of disk clutch has been shown, that the rings 25 have been, and are being applied to many different forms of disk clutches, the only necessity being that the ring may be applied to the clutch in such a manner that there is no relative movement circumferentially of either of the members with which it is in contact, such a movement tending to wear the 25 spring member in places, and thus impair its usefulness.

Experience with cars equipped with a spring of this character shows that it is possible to start them readily in the high speed without jerking, whereas the same car and 35 the same clutch without this spring produced a very disagreeable acceleration even in low speed.

Having thus described my invention, what I desire to secure by Letters Patent of the 40 United States is as follows, but modifications may be made in carrying out the invention as shown in the drawings and in the above particularly described form thereof, within the 45 purview of the annexed claim.

In a friction clutch of the multiple disk type, an auxiliary pressure compensating device taking the form of a washer-like ring lying between one of the clutch members and one of the relatively non-rotatable clutch 50 disks, said ring being of spring sheet metal and radially corrugated in a manner whereby it may be flattened out when pressure is applied to the disk and will freely transmit throughout the ring unequal stresses developed at any place thereon, so as to compensate for inequality of alignment or pressure 55 of the clutch parts.

In testimony whereof I have hereunto set my hand this 15th day of July, A. D. 1926.

OTTO W. HAHN.
